CLAIM

The ornamental design for a laser cutter, as shown and described.

DESCRIPTION

FIG. 1 is a perspective view of a laser cutter showing my new design.

FIG. 2 is a front view of a laser cutter.

FIG. 3 is a rear view of a laser cutter.

FIG. 4 is a left side view of a laser cutter.

FIG. 5 is a right side view of a laser cutter.

FIG. 6 is a top view of a laser cutter.

FIG. 7 is a bottom view of a laser cutter.

FIG. 8 is a bottom side perspective view of a laser cutter.

FIG. 9 is an enlarged view of a laser cutter taken from the circle part in FIG. 2.

FIG. 10 is an enlarged view of a laser cutter taken from the circle part in FIG. 3.

FIG. 11 is an enlarged view of a laser cutter taken from the circle part in FIG. 3.

FIG. 12 is an enlarged view of a laser cutter taken from the circle part in FIG. 3.

FIG. 13 is an enlarged view of a laser cutter taken from the circle part in FIG. 4.

FIG. 14 is an enlarged view of a laser cutter taken from the circle part in FIG. 5.

FIG. 15 is an enlarged view of a laser cutter taken from the circle part in FIG. 7; and,

FIG. 16 is an enlarged view of a laser cutter taken from the circle part in FIG. 6.

The broken lines in the drawings depict portions of the laser cutter that form no part of the claimed design.

1 Claim, 16 Drawing Sheets
